MACHINE FOR MIXING ROAD MATERIAL AND THE LIKE

Original Filed Nov. 2, 1921 2 Sheets-Sheet 2

Patented Mar. 15, 1927.

1,621,099

UNITED STATES PATENT OFFICE.

THOMAS J. BARRETT, OF BORDENTOWN, NEW JERSEY.

MACHINE FOR MIXING ROAD MATERIAL AND THE LIKE.

Application filed November 2, 1921, Serial No. 512,394. Renewed November 21, 1925.

My invention relates to apparatus employed for the mixing of road-building material where it is desired to thoroughly incorporate the mineral ingredients thereof with an asphaltic or bituminous binding material, with or without the addition of a special solvent for such binding material, which in some instances, may be burnt out when the material is placed upon the road-bed. My invention also relates to an improved process or method of treatment, which may be carried out in my improved apparatus.

One object of my invention is to provide a simple and efficient mixing machine, which may be power driven, wherein I can effect rapid mixing of the road material and at the same time completely coat each particle of the mineral aggregate with the desired binding agent.

A further object of my invention is to mix the material in such manner that it will be elevated into contact with the air in order that the mass may be thoroughly aerated; the air mixed with the same assisting in the gasifying or vaporizing of the solvent when employed and rendering the latter readily susceptible of being burnt out should such method of procedure be carried out in the utilization of the material in the formation of a road.

A further object of my invention is to provide a special form of mixing blade, which may be right- and left-handed, and designed to lift and agitate the material being mixed in order that all portions of the same may be brought into contact with the air; such mixing blades not only raising the material during the mixing operation but also moving the same laterally from end to end of the machine.

A further object of my invention is to so arrange said mixing blades that the material being mixed will be moved or carried from the ends of the mixing chamber toward the center of the same during the discharge of such material from the mixing chamber.

A further object of my invention is to provide a structure wherein the agitating and mixing blades will be so disposed and of such a character as to completely clean the surface of the mixing chamber so that the whole body of the mixture may be completely discharged.

And a still further object of my invention

is to arrange the mixing chamber with a movable door; such door closing an opening which may be centrally disposed at the side of the chamber through which the contents thereof may be discharged by continuing the operation of the mixing blades after opening said door, and without the necessity of tilting the mixing chamber.

These and other features of my invention are more fully described hereinafter; reference being had to the drawings, in which:

Figure 1, is a longitudinal sectional view of a mixing chamber within the scope of my invention.

Fig. 2, is a cross sectional view, on the line II—II, Fig. 1.

Fig. 3, is a side elevation of the mixing chamber, and

Figs. 4, 5 and 6, are views of the special form of stirring or mixing blade which I employ in my improved mixing machine; Figs. 5 and 6, being sectional views on the lines V—V and VI—VI, Fig. 4, respectively.

My improved mixing chamber is preferably mounted upon a portable structure, which may also carry driving means. Such arrangement is not essential however, and the mixing blades may be hand-driven if desired. As illustrated in the drawings herewith, my improved apparatus may comprise a tank or receptacle 1, mounted upon a suitable frame work or body 2, having wheels 3. This body may also carry a prime mover, shown in dotted lines, which may be any ordinary type of internal combustion engine, indicated at 4. Through the medium of suitable gearing indicated at 5, 6, 7 and 8, and a clutch element 9, a shaft 10, passing through the mixing chamber 1, may be driven, and with it the several mixing blades, as hereinafter described. As indicated, this shaft may be hand-driven, with or without the interposition of gearing, by attaching a crank handle thereto.

A suitable mixing chamber is provided by the tank 1, and the shaft 10 passing through the same may be journaled in bearings 11 and 12, carried by suitable supports 13 and 14, mounted on the body of the apparatus. If desired, the wall of the tank forming the mixing chamber may be hollow, providing the space 15 and, when employed, the products of combustion and gases exhausting from the engine may be delivered to the space provided by said hollow wall so as to

provide some heat during the mixing operation.

The mixing chamber is preferably semi-circular in cross section, and the shaft 10 may carry at each end, adjacent to the end walls of the chamber, a pair of cutting and scraping blades 16, which I have termed plows; the function of which is to scrape from the curved wall of the chamber, as well as said end walls, the material within the chamber, in addition to thoroughly agitating the same, and said plow blades are so shaped and disposed as to have a tendency to move the material agitated and scraped from the end walls of the same toward the center of the mixing chamber.

Intermediate the sets of plow blades at the ends of the mixing chamber, are a series of other mixing blades of a special type, indicated at 17, each of said blades being adjustably carried by an arm 18, secured to the shaft 10, by clamp members 19. The arms may have toothed seats 20 for engagement by similarly toothed portions 21, of the blades; said arms being slotted at 22 for the passage of retaining bolts 23, and permitting adjustment of the blades with respect to said arms.

These blades 17 are of a special shape and character as clearly indicated in Figs. 4, 5 and 6; having an outline substantially rectangular at one end comprising the discharge edge 17^a, and the side edges 17^b and 17^c, and being semicircularly curved at the opposite end as indicated at 17^d; the semicircularly curved portion projecting laterally at one side of the blade beyond the plane of the edge 17^b and joined to the edge 17^c by a substantially straight portion 17^e diagonally disposed with respect to the edge 17^b. These blades are also right- and left-handed, as clearly indicated in Figure 1. In addition, each blade is hollowed out in planes substantially at right angles to each other in substantially bowl-shaped form, whereby a discontinuous raised edge is provided around such blade made up of the portions 17^b, 17^c, 17^d and 17^e. This structure is, in effect, a bowl-shaped scooping blade with a free discharge end, and its function is to scoop up the material during rotation and carry it upwardly, outwardly and toward the center of the mixing chamber; the character and shape of the blade permitting the material picked up thereby to drop laterally from the lateral extension of the same when said blade is in the uppermost position, this lateral displacement of the material insuring movement of the same within the mixing chamber longitudinally thereof and insuring further that each blade will always be engaging fresh portions of the material during the rotative movement.

The blades lift the material from the bottom of the mixing chamber and raise

the same by the scooping action, instead of merely cutting through the material being mixed, as is common with ordinary mixing machines. By this means the material is completely aerated, and any solvent agent employed is mixed with the air and is in better condition for the subsequent burning out of the solvent, if such operation is carried out.

The shape and arrangement of the hollowed blades is such that the material will not only be lifted thereby, and approximately to the height attained by such blades when rotating, but such material in dropping from the same will be carried laterally and moved from end to end of the mixing chamber.

A plurality of these blades are disposed on opposite sides of the center of the mixing chamber, in the present instance in sets of three, with a blade centrally disposed, so that while the blades at one end tend to move the material in one direction, the other blades tend to move it in the opposite direction, both movements being toward the center of the mixing chamber. As the material being mixed will naturally gravitate to the bottom of the chamber during the mixing operation, there is always sufficient material present at the ends of the mixing chamber for the blades to act upon.

At the side of the mixing chamber, I may provide a discharge opening 25, normally closed by a door or gate 26, which preferably follows the contour of the mixing chamber, and flanges 27, may be provided to guide the door so that it may be readily raised and lowered as desired. These flanges may carry anti-friction rollers 28, to assist the movement of such door or gate.

It will be at once apparent that by having blades which tend to throw the material toward the center of the mixing chamber and at the same time lift it, such material may be discharged from the mixing chamber as soon as the door or gate is opened, the lower edge of the opening being sufficiently close to the bottom of the chamber to permit the blades to elevate the material out through the same for delivery to a suitable receptacle such as a wheel-barrow, or other collector, by which it may be carried to any desired point.

In order that the door or gate may be operated, I may provide a lever 30, loosely hinged on a pivot pin 31, the connection between these parts being such as to permit such lever a certain amount of lateral motion in addition to the up and down motion that will be imparted to it in order to open the door or gate. The end 32, of said lever, may be connected to a link 33, the opposite end of which link is connected at 34, to the bottom of the door. By means of such

arrangement, the door may be readily raised or lowered in the guide flanges 27 carried by the side of the mixing chamber.

While I have referred to my improved 5 mixing chamber as intended for mixing road-building material and for coating the mineral ingredients thereof with an asphaltic or bituminous binding agent, it may be employed for the mixing of concrete or 10 other materials without departing from my invention.

I claim:

1. A revolving mixing blade for a horizontal mixing chamber, comprising a hollowed body with an open outer edge for the mixing chamber periphery and a raised margin around the rest of its perimeter. 15

2. A revolving mixing blade for a horizontal mixing chamber, comprising a bowl-shaped body with a substantially straight, open scraping and discharge margin for 20 cooperating with the mixing chamber periphery.

3. As a new article of manufacture, a 25 mixing blade comprising a hollowed substantially scoop-shaped body having a substantially rectangular portion with a straight edge at one end, and curved at the opposite end to provide a bowl-shaped 30 lateral extension projecting to one side of the substantially rectangular portion, with a discontinuous marginal edge extending substantially all around the same, and terminating at opposite ends of said straight 35 edge.

4. As a new article of manufacture, a 40 mixing blade comprising a hollowed body substantially rectangular at one end and curved at the opposite end, with a discontinuous marginal edge extending substantially around the same to a straight edge at its

rectangular end; said blade being shaped to pick up material, hold it by its marginal edge and discharge it from the straight free edge thereof. 45

5. As a new article of manufacture, a mixing blade comprising a hollowed body substantially rectangular at one end and curved at its opposite end with a discontinuous edge curving up from the body of the 50 same to a straight edge at its rectangular end, with a part of said curved portion extending laterally with respect to the rectangular portion.

6. In a mixing machine, the combination 55 of a shaft, an arm carried thereby, a seat at the outer end of said arm, a scoop-shaped blade with a discontinuous raised edge having a seat engaging the seat at the outer end of the arm; the latter being slotted, and a 60 bolt passing through said blade and the slot of the arm and serving to hold these parts in adjusted positions; said blade having its raised edge portion disposed adjacent the shaft upon which its supporting arm is mounted.

7. In a mixing machine, the combination 70 of a horizontal shaft, an arm carried thereby and having a seat adjacent its end, a scoop-shaped blade having a hollowed body with a discontinuous raised edge and a bowl-shaped lateral extension projecting toward the longitudinal center of the mixing chamber adjacent the axis of rotation; said blade having a seat engaging the seat of the arm and the arm being slotted, and a bolt passing through said blade and the slot of the arm, and serving to hold these parts in adjusted position.

In witness whereof I have signed this 80 specification.

THOMAS J. BARRETT.
